(57) **CLAIM**

The ornamental design for a laser hair removal device, as shown and described.

DESCRIPTION

FIG. 1 is a front and top perspective view of a laser hair removal device, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion “9” shown in FIG. 1. The dash dot dash lines in FIGS. 1 and 9 are for the purpose of illustrating enlarged view indicators and form no part of the claimed design. The evenly spaced broken lines in the figures illustrate portions of the article that form no part of the claimed design.

1 Claim, 9 Drawing Sheets
